FLUID-OPERATED TOOL.

1,117,307.

Specification of Letters Patent. Patented Nov. 17, 1914.

Application filed March 2, 1912. Serial No. 681,682.

To all whom it may concern:

Be it known that I, LEWIS C. BAYLES, a citizen of the United States, residing at Easton, in the State of Pennsylvania, have invented certain new and useful Improvements in Fluid-Operated Tools, of which the following is a specification.

My invention relates to fluid operated tools and more particularly to a valve mechanism for such tools, of the type shown in my previous Patents #985285, February 28, 1911, reissued as #12317, November 21, 1911, and #993014, May 23, 1911.

The object of my invention is to provide improvements in such valve mechanisms, which improvements consist in so arranging the fluid ports and passages that the valve shall be thrown by live fluid pressure on a surface or surfaces of the valve of greater area than the opposed surface or surfaces rather than by compression produced by the piston in the inlet passages acting on said surfaces, as in former valves of this type. This allows the exhaust ports to be placed nearer the ends of the cylinder, which is particularly desirable at the tool end, as the blow or stroke of the piston on or with the tool is, by this construction, very slightly cushioned, and is therefore more effective in operation.

A practical embodiment of the invention is shown in the accompanying drawings, in which only so much of the tool is shown as is necessary to clearly indicate its operation.

In the drawings Figure 1 is a vertical longitudinal view, partly in section, of a tool embodying my invention. Fig. 2 is a section taken in the plane of the line II--II Fig. 1, looking in the direction of the arrow, and Fig. 3 is a section through line III--III, looking in the direction of the arrow.

The tool shown is of the hammer type and comprises a cylinder 1, to one end of which is bolted a handle 2, and in the other end of which is set the tool 3, in this case shown as a rivet set, which is actuated by the impact of the piston 4. On the cylinder is bolted a valve chest 5, with an inlet opening 6, in which can be attached the fluid supply pipe (not shown) and on the opposite side of the valve chest is the exhaust opening 7.

Centrally placed in the valve chest is a cylindrical bore from which radiate paral-

lel-walled valve slots 8 and 8^a communicating respectively with inlet opening 6 and exhaust opening 7. In the cylindrical bore is fitted the longitudinal body portion 9 of the valve from which tapered wings 10, 11, extend into the valve slots 8, the taper of the wings allowing them a slight oscillating movement from one face of the valve slot to the other. In opposite faces of the inlet valve slot 8 are inlet ports 12 and 13, leading by passages 14, 15 to ports 16, 17 in the opposite ends of the cylinder. In the faces of the exhaust valve slot 8^a are two exhaust ports 18 and 19, leading by passages 20 and 21 to ports 22 and 23, which open into the cylinder at points somewhat nearer the middle of the cylinder than ports 16 and 17. In the faces of valve slot 8^a are also two opposed valve operating ports 24 and 25, leading by passages 26 and 27 to ports 28 and 29 near the middle of the cylinder which are so placed as to be alternately uncovered by the piston near the end of its movement in either direction.

The operation of the valve is as follows: When the valve is in position shown in the figures, live fluid enters through the inlet opening 6, and passing through the port 13, passage 15, and port 17 drives the piston toward the tool end of the cylinder, the fluid in front of the piston exhausting through port 22, passage 20 and port 18. When the piston uncovers the exhaust port 23, fluid pressure is created in port 19 against the exhaust wing which covers the port. This pressure, however, is not sufficient to overbalance the opposed pressure from the exhaust port 18 on the opposite side of the exhaust wing in addition to the pressure on the opposed side of the inlet wing. When the piston reaches the position shown in Fig. 1 however, and the port 29 is uncovered, live pressure is exerted against a greater area, the exhaust wing ports 19 and 23 both being in communication with the fluid supply, and this over-balances the opposing pressures, as soon as the exhaust port 22 in front of the piston is closed, and throws the valve. This closes the ports 13, 18 and 24 and allows live fluid to enter the cylinder by port 16, which moves the piston in the opposite direction.

It can be readily seen that by using such a construction and depending upon live fluid pressure to throw the valve, that the exhaust port can be placed comparatively

near the inlet port of the cylinder, and there will be little or no cushioning effect on the piston after the piston passes the exhaust port, thus permitting a sharp and effective blow by the tool. When the piston is moving in the opposite direction toward the handle, it is often not necessary or even desirable to have this partially uncushioned stroke. By reason of this, it will be noticed that in the drawings the exhaust port in the handle end of the cylinder is placed nearer the middle of the cylinder than in the tool end. This allows a slight cushioning on this end. If this port is placed in this way nearer the middle point of the cylinder, the valve on the back stroke will be thrown partially by the compression in the inlet passage and ports which is produced by the stroke of the piston after the exhaust port is closed, the tool approaching in operation the valve shown in my former patents mentioned above. If this exhaust port is placed sufficiently far along the cylinder, the valve will operate on the back stroke without the extra port 23, which may be omitted in such a case without seriously affecting the operation of the tool.

It is understood that the present drawing and description covers only one embodiment of my device and equivalents wherein the ports are so arranged as to throw the valve in substantially the same manner, such as by applying leverage to the wings in a different though equivalent manner, whether with valves rotating in the valve seat or sliding therein as in my Patent #693014, May 22, 1911, are included in my invention as expressed in the claims.

By "opposed faces" are meant faces which if pressure were applied thereto would cause motion in opposite directions, whether on the same or opposite sides of the fulcrum in the oscillating type, or on directly or diagonally opposite sides in the sliding type of my valve.

What I claim is:

1. In a fluid operated tool a cylinder, its piston, a valve having a plurality of wings, inlet and exhaust passages for both ends of the cylinder controlled by said wings and separate passage for conveying live fluid from ports in the intermediate portion of the cylinder to opposed faces of said wings to operate said valve.

2. In a fluid operated tool, a cylinder, its piston, a valve having two wings, inlet passages opening to the faces of one of said wings and exhaust passages opening to the faces of the other wing, said passages being controlled by the movement of said wings, and passage from the cylinder to opposed faces of the exhaust wing for conveying live fluid to move the valve.

3. In a fluid operated tool, a cylinder, its piston, a valve having a plurality of wings, inlet passages leading from the ends of said cylinder to faces of said wings, exhaust passages leading from points nearer the middle of said cylinder to faces of said wings, inlet and exhaust being controlled by the movement of said wings, and passages leading from the intermediate portion of said cylinder to opposed faces of said wings, to convey live fluid to move said valve.

4. In a fluid operated tool, a cylinder, its piston, a valve chest, a valve having a plurality of wings adapted to move in said valve chest, inlet passages opening to faces of said wings and exhaust passages to other faces of said wings, said passages leading to both ends of the cylinder and controlled by the movement of said valve, ports in the cylinder arranged to be alternately put into communication with the inlet ports by the movement of the piston and passages from said ports to opposed faces of said wings.

5. In a fluid operated tool, a cylinder, its piston, a valve chest, said valve chest having a cylindrical bore, and valve slots radiating therefrom, a valve having a cylindrical body portion and tapered wings extending into said valve slots and adapted for oscillation to alternate faces thereof, inlet ports in opposed faces of said slots, leading to the ends of the cylinder, exhaust ports in opposed faces in said slots, leading from ports in the cylinder farther from the ends thereof, and valve operating ports in opposed faces of said slots leading from ports in the cylinder farther from the ends of said cylinder than said exhaust ports.

6. In a fluid operated tool, a cylinder, its piston, a valve chest, said valve chest having a cylindrical bore and two valve slots radiating therefrom, a valve having a cylindrical body portion fitting in said cylindrical bore and tapered wings adapted for oscillation to alternate faces of said slots, inlet ports in opposite faces of one of said slots leading to ports in the ends of said cylinder, exhaust ports in opposite faces of the other of said slots leading from ports in the cylinder nearer the middle point of said cylinder than said inlet ports, and valve operating ports in opposite faces of the exhaust slot leading from ports in the cylinder near the middle point of the cylinder but on opposite sides thereof, said valve operating ports being so placed as to be alternately uncovered by the movement of the piston and thrown into communication with the said inlet ports.

LEWIS C. BAYLES.
